UNITED STATES PATENT OFFICE

173,320

MEMORIAL VASE

William Mellor and Samuel Slade,
Stoke-on-Trent, England

Application March 23, 1954, Serial No. 29,650

Term of patent 3½ years

(Cl. D35—3)

To all whom it may concern:

Be it known that we, William Mellor and Samuel Slade, have invented a new, original, and ornamental Design for a Memorial Vase, of which the following is a specification, reference being had to the accompanying drawing, forming a part hereof.

We claim:

The ornamental design for a memorial vase, as shown.
